(57) **CLAIM**

The ornamental design for magnifying glasses, as shown and described.

DESCRIPTION

FIG. 1 is a front view of the present invention with the outer lenses in an up position; and

FIG. 2 is a rear view of the present invention with the outer lenses in an up position; and

FIG. 3 is a right side view of the present invention with the outer lenses in an up position; and

FIG. 4 is a left side view of the present invention with the outer lenses in an up position; and

FIG. 5 is a perspective view of the present invention on a user with the outer lenses in an up position; and,

FIG. 6 is a perspective view of the present invention on a user with the outer lenses in a down position.

Wherein the dotted lines herein form no part of the claimed invention and serve only to illustrate use and environment.
